US0D1071220S

(12) **United States Design Patent** (10) **Patent No.:** **US D1,071,220 S**
(45) **Date of Patent:** **** Apr. 15, 2025**

(54) **OSTEOTOMY WEDGE**

(71) Applicants: **RESTOR3D, INC.**, Durham, NC (US);
DUKE UNIVERSITY, Durham, NC (US)

(72) Inventors: **Andrew Todd Miller**, Durham, NC (US); **Matthew Rexrode**, Durham, NC (US); **Cambre Kelly**, Durham, NC (US); **Ken Gall**, Durham, NC (US)

(73) Assignees: **RESTOR3D, INC.**, Durham, NC (US); **DUKE UNIVERSITY**, Durham, NC (US)

(**) Term: **15 Years**

(21) Appl. No.: **29/879,557**

(22) Filed: **Jul. 10, 2023**

Related U.S. Application Data

(60) Continuation of application No. 29/780,311, filed on Apr. 23, 2021, now Pat. No. Des. 992,116, which is a division of application No. 29/719,881, filed on Jan. 8, 2020, now Pat. No. Des. 920,516.

(57) **CLAIM**

The ornamental design for an osteotomy wedge as shown and described.

DESCRIPTION

FIG. 1 is a perspective view of an osteotomy wedge;

FIG. 2 is a top view of an osteotomy wedge;

FIG. 3 is a bottom view of an osteotomy wedge;

FIG. 4 is a side view of an osteotomy wedge;

FIG. 5 is a side view of an osteotomy wedge;

FIG. 6 is a front view of an osteotomy wedge; and,

FIG. 7 is a back view of an osteotomy wedge.

The broken lines in the drawings are for the purpose of illustrating environmental structure and form no part of the claimed design.

1 Claim, 7 Drawing Sheets
